CLAIM

The ornamental design for a terminal box connector, as shown and described.

DESCRIPTION

FIG. 1 is a front elevation view of a terminal box connector showing our new design.

FIG. 2 is a rear elevation view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a top, front and left side perspective view thereof; and,

FIG. 8 is a bottom, rear and right side perspective view thereof.

The broken line portion of the figures is included to show unclaimed subject matter only, and forms no part of the claimed design.
